UNITED STATES PATENT OFFICE.

WILLIAM ANDREW LEE, OF AUGUSTA, GEORGIA.

PRESS CLOTH.

Application filed October 12, 1921. Serial No. 507,316.

To all whom it may concern:

Be it known that I, WILLIAM A. LEE, a citizen of the United States, and a resident of Augusta, in the county of Richmond and 5 State of Georgia, have invented certain new and useful Improvements in Press Cloths, of which the following is a specification.

My present invention relates generally to what are commonly known as press cloths, 10 that is cloths used for the purpose of wrapping oleaginous seeds and other oil bearing material while the latter are pressed in hydraulic presses, the press cloth acting as a filter through which the oil may be dis- 15 charged and still retain the meal or cake within the cloth.

It is a well known fact that cloths ordinarily formed of hair, jute or other textile fabric are comparatively short lived and 20 that made up as they usually are by weaving twisted strands, the filtering in the main takes place between the twisted strands and not through the material of which the strands are formed.

25 My invention aims in the first place to provide a press cloth in which the usual hair or fabric filtering material is combined with metal in a manner which will bring about a greatly extended life of use as compared to 30 the usual press cloths, and a further object is the provision of such an arrangement which permits the oil to be filtered between the fibers of a material as well as between twisted strands thereof or a fabric made 35 therefrom and one which will not only increase the yield of oil but reduce the amount of meal or cake which passes the usual cloth.

With the above objects in mind, my invention resides in a press cloth constructed 40 as shown in the accompanying drawings, which illustrate the invention and form a part of this specification and in which,

Figure 1 is a perspective view of a portion of a press cloth constructed as proposed by my invention,

Figure 2 is a longitudinal section through a portion thereof,

Figure 3 is a partial transverse section taken on line 3—3 of Figure 2,

50 Figure 4 is a detail perspective view of one of the tubular filtering material holders,

Figure 5 is a longitudinal section showing a slightly modified form,

55 Figure 6 is a perspective view of a pair of the holders constructed and joined as in Figure 5,

Figure 7 is a perspective view of a section of press cloth showing another modified form,

Figure 8 is a partial transverse section 60 taken on line 8—8 of Figure 9, and

Figure 9 is a partial longitudinal section taken on line 9—9 of Figure 8.

Referring now to these figures and particularly to Figures 1 to 4 inclusive I have 65 shown a press cloth embodying a lengthwise series of transversely disposed and flexibly joined tubular filtering material holders 10, each of these several holders being in the form of a flattened wire helix, the convolutions of the wires being interengaged in overlapping relation as seen clearly by reference to Figure 2 to provide for the reception of transversely disposed hinge pins 70 or wires 11.

The hinge pins 11 securing the several holders in their overlapping relation provide for maximum flexibility throughout the entire press cloth, that is in a lengthwise direction, the several holders and the several hinge pins or wires extending transversely in the press cloth so that with the natural yielding qualities of wire joined in this way it is obvious the finished press cloth will be flexible to the extent of the resiliency of the wire even in a transverse direction.

The term holders for the several flattened wire forms arises from the fact that through each wire helix the filtering material is 90 packed, preferably by drawing the hair, jute or other material lengthwise through the holders so that the latter are completely filled and may if so desired be so filled without the necessity of twisting the filtering material into strands as is done previous to the weaving of the usual all-fabric press cloths. It is obvious that in the first instance this filtering material, indicated at 95 12, may be drawn in sufficient quantity 100 through each of the holders so that the press cloth as a whole is first used, the pressure, which tends to slightly flatten the holders as originally formed, will pack the filtering material snugly around the hinge 105 pins or wires 11 so that thereafter in use there is little danger of escape of any of the meal within the press cloth.

Instead of utilizing the hinge pins or wires 11 to form the flexible connections between the holders, the convolutions of the wire holders may be interlocked, that is the

convolutions of each holder being passed through the convolutions of the next adjacent holders as indicated in connection with the wire holders 13 shown in Figures 5 and 6, the filtering material 12 being passed through each holder as in Figure 5 similar to the manner previously described in connection with Figures 1 to 4 inclusive. Figure 6 clearly shows the manner in which the convolutions of the wire holders are passed through one another so that they are flexibly connected without the necessity of additional parts. It is of course obvious that the wire holders particularly in this form of the invention may be constructed in cylindrical form in the first instance and afterwards flattened.

In Figures 7, 8 and 9 I have shown another possible form of the invention in which metal tubes 14 are utilized, the tubes being formed of a suitable metal and flattened, with their side edges castellated as indicated at 15 to provide for the reception of hinge pins or wires 16. These tubes 14 after flattening to the form shown are perforated throughout, the perforations being indicated at 17 so that the filtering can take place freely through the filtering material 18 through the holders just as previously described in connection with the wire forming holder. It is a well known fact that in the use of press cloths, the ends thereof are folded over the central portion, and although the metal holders 14 of the last described form of the invention may be made sufficiently narrow to provide for this folding, it is contemplated as possible that the complete press cloth may have flexible sections of the usual woven fabric and the like between central and end sections to allow of the proper folding of the cloth.

In any event and with either of the forms shown it is quite obvious that I am enabled to use filtering material in any desired form within the holders, whereby the two materials as thus employed will increase efficiency and obtain an oil in operation which is more pure and much more free of small particles of the mat or cake than is usually the case.

It is also obvious as tests have proven that a mat as proposed by my invention will outlast by many times the usual woven fabric or hair mat and I am thus enabled to greatly reduce the cost of the usual oil extraction operation of this nature.

In filling the holder with the filtering material which may be hair, jute, cotton or anything suitable for this purpose, the

fibers or strands of such material or a fabric formed therefrom are drawn lengthwise through the holders and then cut off and it is of course to be understood that in the formation of those structures proposed by the invention involving the connection of the holders by means of hinge pins or wires, the ends of such hinge pins or wires are bent laterally at the sides of the complete press cloth so as to leave the cloth with substantially smooth side edges in its finished form and lock the wires or pins against accidental displacement.

I claim:

1. A press cloth consisting of a flexibly connected series of transversely disposed hollow metallic holders, and filtering material within the hollow of each holder.

2. A press cloth consisting of a series of transversely disposed metallic holders flexibly connected to one another along their opposite sides, and filtering material within the said holders.

3. A press cloth consisting of a flexibly connected series of transversely disposed metallic holders and a filling of filtering material in each holder consisting of strands of the material extending lengthwise through the holders.

4. A press cloth consisting of a flexibly connected series of transversely disposed pervious tubes, and filtering material within the tubes.

5. A press cloth consisting of a linked series of transversely disposed pervious metallic holders and filtering material within and through the said holders.

6. A press cloth consisting of a series of hingedly connected transversely disposed holders, each formed of a wire helix, and filtering material within and throughout each of the holders.

7. A press cloth consisting of a series of transversely disposed holders, each in the form of a flattened wire helix, the convolutions of which holders are flexibly connected along opposite sides of the holders, and filtering material within each of the holders.

8. A press cloth consisting of a series of transversely disposed holders, each in the form of a flattened wire helix, the convolutions of each of which holders overlap the convolutions of adjacent holders upon opposite sides thereof, hinge pins extending through the overlapped sides of the several holders and serving to flexibly connect the same, and filtering material disposed within and through the holders as described.

WILLIAM ANDREW LEE.
